UNITED STATES PATENT OFFICE.

MICHAEL ROURKE, OF WINDSOR, ONTARIO, CANADA.

BIN-VENTILATOR.

1,272,536.

Specification of Letters Patent. Patented July 16, 1918.

Application filed June 9, 1917. Serial No. 173,900.

To all whom it may concern:

Be it known that I, MICHAEL ROURKE, a citizen of the Dominion of Canada, and residing at Windsor, in the county of Essex and Province of Ontario, Canada, have invented a new and Improved Bin-Ventilator, of which the following is a specification.

It has been proposed to ventilate grain in bins by various constructions which required the use of an air pump or other means for creating pressure or suction whereby air was either forced or sucked through the bin in quantities sufficient to absorb moisture and prevent heating—because of expense and for other reasons these devices have not gone into wide commercial use. It has also been proposed to insert into the bins from above perforated metal shells having pointed ends, but these devices have been discarded because they failed to provide a sufficiently rapid interchange of air and because such moisture as condensed on the shells merely found its way back into the grain.

To the end of overcoming the objections stated, the present invention consists in a double tubular construction arranged to be set up over a hole in the floor of the bin and to form both an inner ingress passage and an outer ingress passage for the air current, the walls of the inner passage being arranged to act as an element upon which a portion of the moisture carried by the air current may condense and from which it may drip without again coming in contact with the grain. The device is inexpensive, may be easily set in place, may be readily manufactured from stock materials in sizes suitable for the various installations, and performs its functions admirably.

40 In the drawing, Figure 1 is a vertical section through a bin equipped with one embodiment of the invention. Fig. 2 is a section on the line 2—2 of Fig. 1.

The bin, which is of the ordinary type, has a floor 1, sides 2, through one of which an opening (not shown) may be provided for filling purposes, and the top 3. The filling opening may be closed entirely or may be left partly open to afford communication with other portions of the granary or building of which the bin is a part.

The floor is provided with one or more openings that are adapted to receive the lower end of an outer perforated metal tube or screen 5 (the apertures being small enough to prevent passage of the grain)

which extends to a higher level than it is intended to fill the bin and which has its weight carried on a suitable collar 6, another function of the latter being to seal the joint between the element 5 and the floor. Co-axial with the screen is a sheet metal tube 7 of the same length which is supported thereon by a suitable cross-bar 8. Instead of the tube 7, a central sheet metal diaphragm extending longitudinally of the screen might be employed, but the construction shown is stronger, cheaper and performs its functions better.

In operation, supposing the grain to be moist and heated, the air between the screen and the tube 7 becomes heated and rises while a colder (due to the fact it does not come in contact with or in close relation to the heated grain) rising current is simultaneously set up in the interior of the tube. The latter, being relatively cold, condenses a portion of the moisture in the heated upwardly passing air current, and the drops flow down and drip from the end of the tube to the ground.

The details of construction may be varied within wide limits without departing from the spirit of the invention, and I do not, therefore, wish to be limited except as indicated by the subjoined claims.

I claim:—

1. A grain bin having a hole in its bottom, a tubular foraminous element surrounding said hole and extending upwardly therefrom, a pipe of lesser diameter arranged within the tubular element and substantially concentrically therewith, the lower edge of the pipe being spaced from the edge of the hole, whereby an upward current of warm moist air is set up in the annular space surrounding the pipe, and whereby moisture condensing on the outer surface of the tube may drip through the hole in the bottom without coming into contact with the grain.

2. A bin having a hole in its bottom, and a screen surrounding said hole and extending upwardly therefrom, a pipe inclosed by the screen, said pipe being of substantially the same length as the screen but of lesser diameter and having its lower end spaced from the wall of the hole, whereby an upward current of relatively warm air is set up in the space between the pipe and the screen and an upward current of relatively cool air is set up within the pipe, and where-

by moisture condensing on the pipe may drip through the hole in the bottom without coming into contact with the grain.

3. A bin having a hole in its bottom, and 5 a screen in sealing engagement with the edge of said hole and extending upwardly therefrom, a tubular member inclosed and supported solely by the screen, said member being of lesser diameter than the screen 10 and dividing the space within the latter into an inner passage and an outer passage, the entrances to both passages being within the limits of the hole in the bottom of the bin.

4. A bin having a hole in its bottom, and 15 a screen in sealing engagement with the edge of said hole and extending upwardly therefrom, a tubular member inclosed by the screen, said member being of lesser diameter than the screen, and a cross bar having 20 its ends received in the walls of the

screen, said tubular member being supported by the cross bar.

5. A bin having a hole in its bottom, and means extending upwardly from said hole to a point above the upper level of the contents of the bin, said means including an outer screen member, the lower end of which is in sealed engagement with the edge of the opening in the bottom, and a tubular inner metallic member spaced from said outer member and substantially co-extensive therewith, whereby air may enter the bin through the space between the members and may escape through the interior of the inner member and whereby moisture condensing on the inner member may drip through the hole in the bottom without coming into contact with the grain.

MICHAEL ROURKE.
